UNITED STATES PATENT OFFICE.

ALBERT B. WOOD, OF NEW ORLEANS, LOUISIANA.

VALVE

1,406,799.

Specification of Letters Patent. Patented Feb. 14, 1922.

Original application filed May 31, 1916, Serial No. 100,845. Patent No. 1,339,997, dated May 11, 1920.

Divided and this application filed March 16, 1920. Serial No. 366,393.

To all whom it may concern:

Be it known that I, ALBERT B. WOOD, a citizen of the United States, residing at New Orleans, in the parish of Orleans and State 5 of Louisiana, have invented certain new and useful Improvements in Valves, of which the following is a specification.

My invention relates in general to an improved form of valve for water mains which 10 is particularly useful in connection with the metering device shown and described in my co-pending application, Serial Number 100,845, issued on May 11th, 1920, as Patent No. 1,339,997, of which application the present one is a division and in which said valve bears a very sensitive relation to the proportional metering parts.

It is the object of my invention to provide a valve the construction of which, while 20 still providing a circular opening will permit flow to take place therethrough, during opening and closing movements substantially as it would take place for example, through a triangularly ported valve which was un- 25 covered from its apex toward its base.

It is also the object of my invention to provide a valve for a water main which will offer a minimum amount of interference to the water flowing therethrough and also the 30 provision of valve stop or positioning means so constructed as to permit the water to flow past practically unimpeded immediately upon opening.

These, together with such other objects as 35 are incident to my invention or may hereinafter appear, I obtain by means of a construction which I have illustrated in preferred form in the accompanying drawing, wherein

40 Figure 1 is a vertical longitudinal section through a water-main valve casing illustrating my invention embodied therein, and Figure 2 is an elevation of the rear face of the valve. Figs. 3 and 4 are diagrams illustrating valve ports of two forms hereinafter referred to.

Referring to Figure 1, it will be seen that I have illustrated therein a portion of a conduit or valve casing 1 such, for example, as is employed to conduct water from a reservoir or other source to a city main. The water enters through the end 2 and flows out through the end 3. The casing may be of any suitable shape, but I prefer to form 45 it as shown, with two chambers 4 and 5, the

chamber 4 being connected to the end 2 and the chamber 5 to the end 3. At its central portion the chamber 4 is made wider as indicated at 6 and in this wider portion is formed an annular cell 7 provided with a 60 screen 8 for preventing trash from entering the annular cell. This cell is connected to a suitable metering device, not shown inasmuch as it forms no part of the present invention.

A valve 9 is located between the chambers 4 and 5 which fits in a seat 10. This valve consists of a hemispherical portion 11 connected to a base 12 by any suitable means, such as a threaded stud 13. The hemispherical portion projects through the seat 10 toward the chamber 4. The diameter of the base portion 12 is preferably made of the same dimension as the maximum diameter of the hemispherical portion 11, there 75 being a plurality of stop or positioning lugs 14 extending radially from the periphery of the base 12. These lugs engage the edge of the valve seat 10 when the valve is closed.

By means of the forked projections 15, pin 16, and bolt 17, the valve is pivotally connected to the lever 18 which hinges upon the cylinder 19.

When the valve opens it swings to the 85 right in the direction of flow and the interior walls of the opening are parallel to the flow lines of the fluid passing therethrough. Its movement is controlled by means of the dash pot 20, piston 21 and links 22 and 23. 90

By making the valve hemispherical and seating it in the manner indicated, I am enabled, during the critical periods of valve opening and closing to secure an opening through which flow takes place substantially 95 as it would through a triangular opening which was uncovered from its apex to its base. This can best be demonstrated by reference to Figs. 3 and 4. In Fig. 3 the main valve has been shown diagrammatically in a slightly open position and in Fig. 4 there has been illustrated a port of a triangular shape which has been opened from an apex toward the opposite base in a line parallel to the base to an extent equivalent to the extent of opening of the main valve. I have found by extensive tests that the governing or controlling opening in a valve of the character of the present valve 9 is the 100 area of the opening extending between the 110

edge of the seat 10 and the main valve in a plane which is parallel to the face of the valve seat. Referring to Fig. 3, let A be the area specified. Then A will equal $\pi r^2 - \pi b^2$, which is equal to $\pi(r^2 - b^2)$, where r is the radius of the hemispherical portion 11 of the valve and b is the radius of the portion within the seat as indicated in Fig. 3. Now by the right triangle $r^2 - b^2$, 5 where m is the distance between 10 and the front face of the lugs 14 which mark the line of valve closure. Substituting, A equals $\pi(m^2)$, whereby we find that the area of the governing opening of the main 15 valve is proportional to the square of the displacement of the main valve from the closed position.

Referring now to Fig. 4 where a is the altitude of a triangular opening or port 24 and 20 c is the base, and considering an opening made by a displacement m' from the apex opposite base c, which is equivalent to a displacement m of the main valve, the area A' 25 of the opening will be $\frac{1}{2} md$, where d is the base of the opening. Now $\frac{m'}{d} = \frac{a}{c}$ from which $d = m' \left(\frac{c}{a} \right)$. Now substituting, A' 30 will be equal to $\left(\frac{1}{2} \frac{c}{a} \right) (m')^2$. In other words, the area of the opening in the triangular valve is proportional to the square of the movement similarly to the opening in the main valve. Therefore, the 35 opening in the main valve and the opening in the triangular port will be proportional throughout the movement of the valve. The rounded or hemispherical shape of the valve will permit trash, etc., to flow freely past 40 the valve without catching and clogging the same.

As illustrative of one of the uses to which such a valve may be put, I direct attention

to the aforesaid application in which I couple the valve to a triangular outlet valve of a proportional meter.

It is essential that some stop or positioning means other than a flange on the base, be provided for the valve in order to avoid undue retardation of the flow. Such a means is 50 simply and satisfactorily embodied in the lugs 14 which present, of course, very little obstruction to the flow of water the slight eddying effect of which is inappreciable.

I claim:

1. In a valve, the combination of a circular valve seat, a spherical-section-shaped valve whose radius is no greater than the radius of the seat, a base to which said valve is connected, the radius of the base being 60 no greater than the radius of the seat and lugs extending from the base to engage the seat when the valve is in position.

2. In a valve, the combination of a valve seat, a spherical-section-shaped valve whose maximum area is no greater than the area 65 of the seat and a plurality of lugs connected to the valve and extending therefrom to engage the valve seat when the valve is in closed position.

3. In a valve, the combination of a circular valve seat and a spherical-section-shaped valve whose area at the base is no greater than the area of the seat whereby no appreciable obstruction is offered to the flow of 75 fluid as it passes the seat.

4. In a valve, the combination of a circular valve seat and a spherical-section-shaped valve whose area at the base is no greater than the area of the seat and stop means for 80 positioning the valve when closed, said stop means not appreciably obstructing the flow of fluid as it passes the seat.

In testimony whereof, I have hereunto signed my name.

A. B. WOOD.
